UNITED STATES PATENT OFFICE.

FRANK D. WINKLEY, OF MADISON, WISCONSIN, ASSIGNEE TO FULLER & JOHNSON MANUFACTURING COMPANY, OF MADISON, WISCONSIN, A CORPORATION OF WISCONSIN.

COMBINED PUMP-JACK AND ENGINE BASE.

980,727.

Specification of Letters Patent.

Patented Jan. 3, 1911.

Application filed July 26, 1909. Serial No. 509,581.

To all whom it may concern:

Be it known that I, FRANK D. WINKLEY, a citizen of the United States, residing at Madison, in the county of Dane and State 5 of Wisconsin, have invented certain new and useful Improvements in Combined Pump-Jack and Engine Bases, of which the following is a specification.

My present invention pertains to pump 10 jacks, and particularly to a new and improved form thereof in which the frame of the jack serves as a supporting means for the jack mechanism, and includes in itself the crank case for the engine, suitable casing for 15 the reduction gearing, and the bearings and supports for the crank shaft and the gearing. The frame of the jack consists of but three 20 pieces,—a base-plate, a combined crank and gear case, and a combined cover-plate and crank shaft bearing.

The structure herein illustrated embodies 25 many of the features described and claimed in United States Letters Patent No. 925,147, granted to me on June 15th, 1909, and no 30 claim will be herein made to anything claimed in said patent. The present invention is, however, designed to add to the utility of the structure and to extend its field as a general farm motor, and at the 35 same time secure a simple and rigid construction.

By the peculiar construction adopted I 40 secure a jack which may be attached to any ordinary type of pump so as to operate the latter in a satisfactory manner, adapt the structure to the reception of any type of cylinder and working parts of an engine, and secure a device which may be readily attached as a whole to an existing pump 45 without the construction of special foundations or supports.

The device is intended particularly for 50 use with an engine of the internal combustion type, and in this case by mounting the batteries, gasolene tank, carburetor, etc., upon appropriate parts of the engine, the device becomes entirely self-contained.

A further and important object of the 55 invention is to render the engine mounted on this base available for other purposes when not used for pumping, or to permit the use of a part of its power for other purposes during the pumping operation. The

outfit is therefore adapted to such purposes as the operation of cream separators, fanning mills, and the like.

A structure embodying the essential principles of my invention is illustrated in the accompanying drawings, wherein:

Figure 1 is a perspective view of a jack 60 attached to a portion of a pump, the connecting mechanism between the jack and the moving parts of the pump being omitted, as are the cylinder and upper portions of the engine; Fig. 2 is a detail sectional view of 65 the casting forming the crank and gear case; Fig. 3 is a detail sectional view of the casting forming the base-plate; Fig. 4 is a sectional elevation taken on the line *b*—*b* of Fig. 5; Fig. 5 is a transverse sectional elevation on the line *a*—*a* of Fig. 4; and Fig. 6 70 is an elevation of the pump with my invention attached thereto.

Like numerals refer to like parts throughout the drawings.

Referring to the drawings, 1 represents 75 the pump to which the jack is attached, and 2 represents the base-plate of the jack. This base-plate is attached to the pump by flanged clamps 3 and 4 held by bolts 5. The height 80 of attachment of the base-plate to the pump may thus be adjusted to suit the needs of each particular case. The forward end of the base-plate 2 is carried by uprights 6, threaded at their upper ends for a considerable distance, and clamped by nuts 7 to the wings or lugs 8 formed on said base-plate. The supports 6 are carried in a sill 9, or may be attached to the floor, and by 85 changing the position of the nuts 7 may be 90 adjusted to the height of the base-plate 2 above said floor. Diagonal braces 10 of strap iron, and a diagonal brace 11 formed of round stock, brace the supports 6 and the sill 9 in two directions, so that sufficient 95 rigidity is secured for the base-plate 2.

Adjacent to the pump are bearings 12 for 100 a transverse shaft 13. This shaft 13 carries on one end a crank 14, and on the other end a large gear 15. The crank 14 is parallel to a spoke 16 of the gear, and the spoke and crank are provided with a series of holes 17 adapted to receive crank-pins 18. To these crank-pins are attached connecting rods 46 (Fig. 4), which are so connected to the piston-rod 47 of the pump as to impart a re-

ciprocating motion to the latter. At the forward end of the base-plate 2 is mounted the casting 19 attached by bolts 20 passing through the flanges 19^a, and the base-plate 2. 5 This casting 19 is provided with a rearward projection 21 adjacent to the base-plate 2, and the base plate 2, casting 19, and its projection 21 are so designed as to form the two halves of divided bearings 22 for a longitudinal shaft 23. The base-plate 2 is further provided with a downwardly projecting lobe or shell 24, which serves as a case and oil pan for a large gear 25 and a bevel gear 26, the latter meshing with the large bevel gear 15, while the former meshes with a small pinion 27 mounted on the engine crank shaft 28.

The form of the lobe or projection 24 is such as to closely envelop the gears, and by 20 retaining the oil which will drip down from the crank case above, will thoroughly lubricate these two gears. The forming of this lobe 24 in the casting tends to reduce its strength, and to reinforce the bed-plate I 25 provide a rib 29 running longitudinally on the under side of the bed-plate and lobe 24, and extending the entire length of the casting.

As already stated, the casting 19 is attached to the base-plate by flanges and bolts, but as clearly shown in Fig. 5, the face of the flanges 19^a do not contact over their entire surface, but are recessed so as to bear only adjacent to the divided bearing 22 and at their edges. Further, the flanges do not extend throughout the length of the contact of the two castings, and where the flanges are not provided the shell of the casting 19 is machined to meet the 30 upper face of the base-plate 2, and form an oil-tight, or approximately oil-tight, joint therewith. In its general form the casting 19 consists of three connected shells or chambers. Of these the largest is the crank case. 35 Projecting rearwardly from the crank case is a second and smaller chamber 30 adapted to form a case for the small pinion 27 carried upon the crank shaft 28. The third chamber is that which forms the upper half 40 of the case for the gears 25 and 26, the lower half being formed as already described, in the base-plate 2.

The crank shaft 28 is mounted at its rear end in a bearing 31 cast integrally with the 45 shell 19, and projecting rearwardly from the gear case 30. The forward face of the crank case is formed with a large opening, and this latter is closed by a plate 32 held by bolts 33. This plate 32 also carries a bearing 34 for the forward end of the crank shaft. This plate may also be provided with bearing 35 to carry igniter, governor, or other mechanism. This bearing is shown merely to represent a means for attaching 50 such devices. Similarly, the gears 36 and

37 are shown merely to illustrate a possible method of driving valve-operating mechanism. These details are largely dependent on the type of engine used, and may be varied at will. It will be noted that by 70 carrying these parts on the plate 32, and by manufacturing a series of interchangeable plates, I might vary my valve mechanism at will, changing only the plate 32 to accommodate the various types. I might 75 thus manufacture two or three types of cylinder and head with different valve gears, governors, igniters, and other details, designed to operate either on the two or four-stroke cycle, and from a commercial standpoint the interchangeable use of all the 80 castings for the base portion is a very valuable feature.

Access is had to the crank case by means of a pivoted cover 38 held closed by a 85 screw clamp 39. The lubrication of the piston is effected by allowing oil to flow into an annular groove 40 formed near the top of the crank case in such a way that the edges of the piston will dip into its contained oil 90 in their lowest position. The upper face of the crank case is provided with a flange 41, to which may be bolted the cylinder. The bearing 31 and the upper half of the bearing 22 are braced together by an interconnecting flange 42, and the crank case is braced to the flanges 19 by ribs 43. The gear guard 44 protects a portion of the face 95 of gear 15.

The above description sets forth a 100 complete structure operating as a pump jack. The additional feature, namely, the means for deriving power from the engine for other purposes, is as follows: The shaft 23 projects beyond its bearings at the forward 105 end, and is provided with a pulley 45 to which the device to be driven may be belted. The gearing ratios may readily be designed to give the best speed for the particular 110 purpose, both to shaft 23 and shaft 13. For instance, in a practical embodiment of the 115 device it has been found desirable to use a motor running at about 500 revolutions per minute, and it has been found that about 30 strokes per minute of the pump was the best adapted to the general run of pumps in common use. These two speeds being determined, it was simple to so adapt the ratios of gears 27 and 25 and 26 and 15 that the pulley 45 should revolve at a speed of 120 155 revolutions per minute, which was believed to be a good average speed. Further speed changes may be controlled by the size 115 of the pulley belted to the pulley 45.

The mechanism constructed as above set 125 forth possesses several advantages. It is readily attached to any type of pump and secures a rigid self-contained structure requiring no special foundation to support it. While primarily intended as a pump jack, 130

the engine is none the less available as a source of light power for other purposes, without detaching the base from the pump and without regard to whether or not the 5 engine is operatively connected to the piston-rod of the pump. This is a particularly desirable feature on farms and in rural districts, this being the purpose for which the outfit was originally designed. The possibility of using various types of engine with 10 the same base casting and the readiness with which the whole device may be removed from the pump or taken apart without so detaching it, are also valuable characteristics. 15

It is believed that the operation of the device will be understood without a detailed description, and consequently none is given.

Having thus described my invention, what 20 I claim is:—

1. The combination of a pump-body; a pump rod; a base-plate adapted to incase gearing; means for attaching the base-plate to the pump-body; auxiliary supports adjustably connected to the base-plate; a shaft 25 mounted in the base-plate; a second shaft also mounted in the base-plate; gears connecting said first and second shafts; means for operatively connecting the first shaft to the pump-rod; means for driving machinery from the second shaft; an internal combustion engine mounted on the base-plate and having a crank case adapted to inclose gearing; and gears mounted in the 30 crank case and connecting the engine to said second shaft.

2. The combination of a pump-body; a pump-rod; a base-plate adapted to incase gearing; means for attaching the base-plate to the pump-body; auxiliary supports adjustably connected to the base-plate; a shaft 40 mounted in the base-plate; a second shaft also mounted in the base-plate; gears connecting said first and second shafts; means for operatively connecting the first shaft to the pump rod; means for driving machinery from the second shaft; an internal combustion engine mounted on the base plate and having a crank case adapted to inclose gearing; and gears mounted in the crank case 45 and connecting the engine to said second shaft, the above-enumerated gears forming a speed-reducing train from the engine to the first shaft, so proportioned that the sec-

ond shaft runs at a speed intermediate that 55 of the engine and the first shaft.

3. A frame for a combined pump-jack and engine-base, comprising, in combination, a base-plate adapted to be attached to a pump structure; adjustable auxiliary supports attached to the base-plate; a combined crank and gear case attached to the base-plate; and suitable bearings formed in said case and base-plate for the reception of shafting. 60

4. A pump-jack comprising, in combination, a frame member including in one structure gear casing and an engine crank case adapted to receive and support the cylinder and moving parts of an engine; a pump-operating mechanism carried and incased by 70 said frame member and adapted to be driven by said engine; means for attaching said frame member directly to a pump structure; and adjustable supports for the frame member. 75

5. A pump-jack comprising, in combination, a frame member including in one structure gear casing and an engine crank case adapted to receive and support the cylinder and moving parts of an engine; a pump-operating mechanism carried and incased by 80 said frame member and adapted to be driven by said engine; a pulley carried by said pump-operating structure adapted to be connected to machinery other than the 85 pump; means for attaching said frame member directly to a pump structure; and adjustable supports for the frame member.

6. The combination of a pump-body; a pump-rod; a base-plate; pump-operating mechanism operatively connected to the pump-rod and carried by the base-plate; an internal combustion engine carried by the base-plate and in driving relation with the pump-operating mechanism; clamps for attaching the base-plate to the pump-body; a sill; a support connected thereto; threaded connections adjustably attaching the support to the base plate; and diagonal braces between the sill and base-plate. 95 100

In testimony whereof I have signed my name to this specification in the presence of two subscribing witnesses.

FRANK D. WINKLEY.
